(57) **CLAIM**

The ornamental design for a basket blank, as shown and described.

DESCRIPTION

FIG. 1 is a top perspective view of a basket blank in accordance with a first embodiment;

FIG. 2 is a top plan view thereof, the bottom plan view being identical;

FIG. 3 is front elevation view thereof;

FIG. 4 is a rear elevation view thereof;

FIG. 5 is a left-side elevation view thereof;

FIG. 6 is a right-side elevation view thereof;

FIG. 7 is a top perspective view of a basket blank in accordance with a second embodiment;

FIG. 8 is a top plan view thereof, the bottom plan view being identical;

FIG. 9 is a front elevation view thereof;

FIG. 10 is a rear elevation view thereof;

FIG. 11 is a left-side elevation view thereof; and,

FIG. 12 is a right-side elevation view thereof.

The evenly spaced broken lines represent parts of the article forming no part of the claim. The dot-dash broken lines represent fold lines forming part of the claim. The dot-dot dash broken lines represent symbolic breaks forming no part of the claim. The appearance of any portion of the basket blank between the break lines forms no part of the claimed design.

1 Claim, 12 Drawing Sheets
